UNITED STATES PATENT OFFICE.

HERBERT WILLIAM ALLEN, OF FRESNO, CALIFORNIA.

CARBURETOR.

Application filed January 25, 1922. Serial No. 531,799.

This invention relates to carburetors especially adapted for application to the power units of motor vehicles and flying machines of various types.

5 Briefly stated an important object of this invention is to provide a carburetor having novel means for supplying a mixture of air and fuel in such relative proportions as to produce the best results in the engine under 10 the specific conditions of load and altitude under which it may be operating at any given time and to supply this mixture in a thoroughly gasified condition and at a temperature as low as is consistent with the fuel being used.

Further an important aim of the invention is to provide a carburetor wherein the fuel level may be maintained substantially below 20 the discharge end of the spray nozzle for eliminating the irregular action of the carburetor when the engine is abruptly tilted or inclined as the result of the travel of the vehicle over rough roads.

The invention forming the subject matter 25 of this application is also provided with means for utilizing fuels of different grades, the lower grade fuel being thoroughly heated and gasified prior to its final mixture with a proper proportion of air.

30 Other objects and advantages of the invention will be apparent during the course of the following description.

In the accompanying drawings forming a part of this application and in which like numerals are employed to designate like parts throughout the same,

Figure 1 is a perspective of the improved carburetor.

Figure 2 is a group perspective of a fuel control mechanism embodied in the invention.

Figure 3 is a detail sectional view through a nozzle and associated elements.

Figure 4 is a vertical sectional view 45 through the improved carburetor.

Figure 5 is a horizontal sectional view through the carburetor, the view being taken on line 4—4 of Figure 4.

In the drawings wherein for the purpose of 50 illustration is shown a preferred embodiment of the invention the numeral 10 designates a casing having its upper portion provided with a nipple 11 provided with radially arranged lugs 12 upon which the flared lower end 13 of a tubular member 15 is mounted. Figures 1 and 4 clearly illustrate that cap

screws 16 are extended through the flared portion 13 of the tubular member 15 and are engaged with the radially arranged lugs 12 for the purpose of securely connecting the 60 enlarged portion 13 to the casing. It will be seen that since the radially arranged lugs 12 are arranged in spaced relation, a substantial air inlet space is provided for permitting a sufficient quantity of air to enter the enlarged tubular portion 15. The upper end of the tubular portion 15 is provided with a coupling member 18 having a flange 19 connected to the attaching flange 20 of the intake manifold 21 by means of cap screws 23 or the like. A butterfly valve 25 is arranged in 65 the coupling member 18 and is provided with an arm 26 having connection with a control rod 27 which extends to a suitable point of control. The butterfly valve 25 is the throttle 70 valve.

The high grade fuel or the priming fluid is fed into a fuel pipe 29 having a valve 30 connected to the upper portion of the casing 10 and having communication with a passage 31 which in turn communicates with an annular passage 32 in the nipple 11.

As illustrated in Figure 4 a choke tube 34 is threaded into the nipple 11 and is provided with an annular flange 35 having its upper side recessed or dished to provide a valve seat for the lower end of a sleeve valve 37. The annular flange 35 is also provided with a series of openings 38 which communicate with the annular passage 32.

When the engine is at rest the valve 37 is down against its seat, and in the preferred embodiment of this invention the high grade fuel may be maintained at a level below the top of the openings 38 by any suitable means. 95 When the engine is started the partial vacuum produced by the engine pistons causes the valve 37 to rise from its seat, and the reduced pressure at the same time, causes high grade fuel to issue through the openings 38 where it is picked up by the air entering between the sleeve valve 37 and the flange 35, and is carried into the engine cylinders through the tubular member 15 and engine manifold 21.

The sleeve valve 37 which is controlled by the vacuum caused by the operation of the engine pistons is provided with an annular rib 40 which operates between an annular shoulder 41 in the tubular member 15 and the lower end of the coupling member 18. The space between the annular rib 110

40 and the annular shoulder 41 is supplied with air by means of a series of openings 43 in the shoulder 41. By thus supplying a quantity of air to the space between the 5 rib 40 and the annular shoulder 41 the valve 37 may move upwards without creating a vacuum in the said space, and likewise the valve 37 may move downwards without compressing the air in the space between the 10 annular shoulder 41 and the rib 40.

As illustrated particularly in Figure 4 the choke tube 34 is arranged at the outlet end of the passage 46 in the casing, the said passage 46 having communication with the outlet branch of the U-shaped heating tube 47. The tube 47 is arranged within an exhaust conveying pipe 48 so that the exhaust gases will come in contact with the tube 47 and thereby volatilize the fuel in the same.

20 The passage 46 has a butterfly valve 49 interposed in it. This butterfly valve has an arm 51 connected to a link 52 which is connected to the arm 53 of the valve 30, as illustrated in Figure 1, so that the fuel control 25 valve 30 and the butterfly valve 49 are operatively connected, the arrangement being such that when the valve 30 is opened for admitting fuel through the pipe 29, the butterfly valve 49 will be closed, thereby closing the 30 passage 46. On the other hand when the valve 49 is opened the partial vacuum in the casing 15 will cause fuel to be sprayed into the gasifying tube 47 and to be drawn through it and through the passage 46, while, 35 at the same time the valve 30 will be closed, thus cutting off the fuel supply from 29. The elements described in this paragraph therefore constitute means whereby fuel may be drawn from either of the two sources noted.

40 As illustrated in Figures 3 and 4 a nozzle 55 is adapted to supply liquid fuel to the U-shaped heating tube 47 from a chamber 8 in the lower portion of the casing 10. The axis of the spray nozzle 55 is in alignment with that branch of the tube 47 connected with the nipple 56 and a choke member 58 is fitted into the nipple 56. This choke member 58 is so formed as to produce a decided constriction of the air passage 45 between the choke member 58 and the outside of the nozzle 55 at a point just below the top of the nozzle 55. This constriction is for the purpose of producing, and is so adjusted in dimensions as to produce, a lowering of pressure at the upper end of the nozzle so that the atmospheric pressure acting on the surface of the liquid in the chamber 60 is transmitted through the liquid fuel to the end of the nozzle 55 and causes the 50 liquid fuel to issue from the nozzle where it mixes with the air entering through a plurality of openings 61 and passes on to the tube 47.

The second constriction produced by the 55 choke member 58 and the metering pin or

needle valve 63 is for the purpose of producing a still higher velocity of the air and liquid fuel in order to more completely break up the liquid fuel into a fine spray. Another definite function of the second constriction formed by the metering pin and the choke member and to a lesser extent the first constriction is to limit the amount of air admitted at this point to the least possible amount consistent with the production of a fine spray. It is not intended to provide air at this point primarily for evaporating the liquid fuel but as a means for spraying the liquid into the heating tube.

By thus limiting the amount of air admitted to the heating tube specific and marked advantages are obtained as will be hereinafter set forth.

The liquid fuel is supplied to the nozzle 55 from the chamber 8 which in turn is supplied with fuel from the float chamber 60 having a float 66 connected to a needle valve 67 by means of a lever 68 pivoted intermediate its ends to a pin 69. When the level of the liquid in the chamber 60 rises the float is elevated and the pin 67 is seated thus cutting off the supply of fuel from the fuel supply pipe 70. In practice the fuel in the chamber 60 is maintained at a level above the chamber 8 and below the top of the nozzle 55.

The metering pin or needle valve 63 is slideable in a bushing 72 threaded into a nipple 73 in the lower portion of the casing 10. A plug 74 is threaded into the lower end of the bushing 72 and may be removed when it is desired to engage a screw driver with the slotted lower end of the metering pin 63 for the purpose of adjusting the same. The proper opening in the spray nozzle for an idling condition is secured by adjusting the height of the metering pin 63.

This adjustment is secured by turning the metering pin 63 in a nut 75 threaded on the intermediate portion of the pin. The nut 75 has laterally projecting pins 80 which are received in longitudinal slots formed in the forked arm of the lever 76 which is pivoted intermediate its ends as indicated at 77. A coiled spring 82 is confined between the face of nut 75 and bushing 72 and forms a means for urging the metering pin 63 upward, whereby the lost motion between the metering pin and the valve 37 is taken up.

With particular reference to Figure 2 it will be observed that the valve 37 is provided with a spider 85 to which a vertically movable rod 86 is connected. The lower end of the rod 86 is provided with a laterally projecting arm 87 arranged beneath the adjacent portion of the lever 76 and having engagement with the roller 90 carried by one of the laterally directed terminal portions of a link 91. The roller 90 operates between the opposed sides of the arm 87 and the lever 76 and may be adjusted longitudinally of the same members.

When the roller 90 is set close to the pivot pin 77 the movement of the lever 76 will be increased when the valve 37 is elevated. On the other hand when the roller 90 is set close to the rod 86, the movement of the lever will be lessened, thus correspondingly decreasing the movement of the metering pin 63 for a given movement of valve 37.

The link 91 is provided with a laterally directed terminal portion having connection with an adjusting screw 93 slidable through a stuffing box 94 at one end of the chamber 8 and having connection with an adjusting nut 95. The adjusting nut 95 is held against endwise movement by means of a holding arm 96 extended from the casing. It is thus apparent that the rotation of the nut 95 will result in the endwise movement of the adjusting screw 93 so that the position of the roller 90 may be varied at the will of the operator.

It is evident that when a more viscous fuel is being used a greater lowering of the metering pin will be required than when a less viscous fuel is being used. The above described arrangement is provided to make the carburetor adaptable to different fuels having different viscosities.

The vertically movable rod 86 is slidable through a bearing 98 extended up through the passage 46 and cooperating with the choke member 34 in reducing the fuel passage in cross sectional area.

By depending principally on heat to produce vaporization of the fuel in the tube 47 a much quicker response is obtained. Some carburetors are slow to respond to increased demands on the engine especially when using lower grade fuels such as kerosene, but that after a few seconds at the most, the motor responds in a satisfactory manner.

In practice it has been found that by spraying the fuel into the interior of a hot tube and depending mainly on the heat to produce the vaporization of the fuel as is the case in this invention, an instantaneous response is obtained to increased demands so that an automobile equipped with this carburetor accelerates as readily when using kerosene as when using a higher grade fuel such as gasoline.

In some other carburetors when the total air or a considerable portion of it passes through the vaporizing tube it has been found difficult to obtain a tube of such dimensions as to give a satisfactory result at all loads especially when using the lower grade fuels. A tube which can be satisfactorily heated when the motor is running on light load tends to become excessively heated on heavy loads. By cutting down the quantity of air admitted to the gasifying tube to a minimum as herein set forth and at the same time reducing the size of the gasifying tube and leading all the products of combustion past the outside of said tube, the increased amount of heat extracted from a gasifying

tube by the greater amount of fuel is balanced at heavier loads by the greater amount of heat given off by the exhaust gases to the gasifying tube so that perfect vaporization without excessive heating of the gasifying tube is obtained at all loads.

I am aware that the utilization of the Venturi principle in connection with the spray nozzle in the carburetor is in a broad sense not novel. Specific improvement is claimed in the use of a very restricted opening so located that the atomizing air first passes this restricted opening before it comes in contact with the liquid fuel or before it reaches the point at which the liquid fuel issues from the spray nozzle. In this manner the velocity of the air is greatly increased at the point at which it contacts with the liquid fuel. By the use of such a very restricted opening in connection with the pressure regulating valve 37 the velocity of the air is maintained practically constant past the discharge end of the nozzle 55 regardless of the load on the engine. In this manner a very efficient spray is produced at the slowest speeds of the engine 90 while the valve 37 provides means for the very free passage of ingoing air when the engine is working at high speed and under heavy load.

It has been found desirable to employ the second constriction between the metering pin and the choke member 58 as the employment of only one constriction would make necessary the use of an extremely small opening in the spray nozzle. Such an opening is hard to regulate and is liable to clog with foreign matter. Also by employing the second constriction as illustrated in the drawing the use of a larger opening in spray nozzle is possible. The second constriction located between the metering pin 63 and choke member 58 serves the additional purpose of producing a finer spray with the same quantity of air than is possible by using a single constriction. As is well known, some carburetors, when adjusted to give a suitable mixture of air and fuel when operating at lower altitudes, give a mixture which is too rich in fuel when operating at higher altitudes. This tendency of the mixture to become too rich at higher altitudes is automatically compensated for in the present carburetor by maintaining the proper proportions between the spray nozzle, the several constrictions, the size of the gasifying tube and the passage 46 and more particularly by providing the proper sized opening in the choke member 34. When fuel is volatilized in an arrangement as shown, it is evident that a given volume of the liquid fuel when vaporized at higher altitudes will expand to greater volume than the same amount of liquid vaporized at lower altitudes due to its being subjected to less pressure at higher altitudes. Therefore at higher altitudes greater differ-

ence in pressure between the gas in the passage 46 and the mixture in the tubular member 15 will be required to force the greater volume of gas through the choke member 34. 5 It is therefore apparent that other conditions being identical greater back pressure will be produced by the vaporized fuel in the chamber 46 at higher altitudes and since as hereinbefore set forth the valve 37 maintains a 10 practically constant difference of pressure between the mixture in the casing and the outside air it is evident that the greater back pressure produced in the casing 46 and gasifying tube at higher altitudes acts to decrease 15 the effective pressure difference causing the fuel to feed through the spray nozzle and consequently less fuel is fed from the nozzle to the gasifying tube. This lesser amount of fuel compensates for the lesser weight of air 20 passing into carburetor and engine at higher altitudes, and a desirable ratio of fuel and air is maintained.

While the pressure regulating valve 37 is shown as a sleeve valve, it is obvious that any 25 suitable form of valve may be employed.

It is well known that most carburetors when adjusted to give a suitable mixture in cold weather give a mixture which is too rich in warm weather or on hot days. 30 This difficulty is partially compensated for in this carburetor through the medium of the same elements that compensate for the changes in air pressure caused by changes in altitude. It is evident that other conditions

being identical when the outside air is warmer 35 the carburetor and its gasifying tube is warmer than on cold days and that in general the carburetor and the liquid fuel contained therein is warmer when the gasifying tube is warmer. The higher the temperature 40 to which the fuel is heated in the gasifying tube the greater its volume and the greater the consequent back pressure generated in the gasifying tube. This greater back pressure tends to decrease the effective pressure feeding the liquid fuel into the gasifying tube and this decrease in effective feeding pressure tends to decrease the flow of fuel and partially compensates for the tendency to greater flow caused by decrease in viscosity of the 45 liquid fuel at higher temperatures and a desirable ratio of fuel to air is maintained. 50

Having thus described my invention what I claim is:—

A carburetor comprising a liquid fuel 55 spray nozzle, a heating tube having an expanded end in communication with the spray nozzle, a choke tube having one end in communication with the remaining end of the heating tube and its other end in communication with the outlet of the carburetor, said heating tube having the opposite end thereof expanded for a portion of its length, said heating tube being U-shaped and of restricted 60 diameter throughout the greater portion of its length and between the expanded ends thereof. 65
